UNITED STATES PATENT OFFICE.

CARL G. SCHMID, OF INDIANAPOLIS, INDIANA, ASSIGNOR TO INSLEY MANUFACTURING COMPANY, OF INDIANAPOLIS, INDIANA, A CORPORATION OF INDIANA.

HEADFRAME FOR MAST HOISTS.

Application filed November 16, 1925. Serial No. 69,248.

My invention relates to improvements in material handling apparatus and has particular reference to the type of apparatus for elevating such material as wet concrete and the like to a predetermined height and then delivering the same by conveyor chutes to the point at which it is desired that the material be deposited.

One of the objects of my invention is to provide an improved means for supporting and mounting the head frame and associated parts to which the material is delivered from the elevating bucket.

For the purpose of disclosing my invention I have illustrated one embodiment thereof in the accompanying drawings in which

Fig. 1 is a side elevation of a mast hoist and its accompanying equipment embodying my invention;

Fig. 2 is a detail in rear elevation of the head frame;

Fig. 3 is a plan view of the head frame, and

Fig. 4 is a detail view showing the dumping mechanism of the bucket.

In the embodiment of the invention illustrated I provide a mast 1 on which the various parts are suitably supported and which preferably comprises four angle iron posts 2 suitably laced together by lacing and bracing strips 3. This mast has operating thereon a suitable dumping bucket 4 which is moved vertically on the mast by operating cables. At the elevated or delivery point of the bucket on the mast there is provided a head frame including a receiving hopper 5 into which the bucket 4 is adapted to dump. This hopper is preferably mounted on the front side of the mast and on the same side as the hoisting bucket. I use the expression "front side of the mast" as designating that side away from the point of delivery. However this term is relative and is merely for the purpose of distinguishing the different sides of the mast rather than specifically positioning the parts with respect to any particular building or apparatus.

The receiving hopper delivers to a suitable chute 6 which projects to the opposite side or rear face of the mast and in turn delivers the material to the hopper head 7 of the conveyor chute 8. This conveyor chute at its inner end is supported from and adjacent to the mast and is inclined downwardly and outwardly to deliver into a second chute or to any selected point of delivery. The conveyor chute

has its outer end supported from the mast by means of a suitable guy cable 10 which preferably extends from a point near the top of the mast to the outer extremity of the chute.

In addition to the bucket 4 I provide on the inner face or rear face of the mast a vertically movable hoisting platform 11 which may be operated by suitable hoisting cables 12 and which may be used for elevating material of various kinds.

Near the upper end and on the inner face of the mast I mount a supporting frame which comprises the vertical members 13 connected at their tops and bottoms by cross members 14 and suitably braced by diagonal braces 15. This frame is connected to the posts by inwardly extending arms 16 projecting from the tops and bottoms of the side members towards the mast and provided with guide lips 17 which embrace the edges of the angle posts 2. Securing bolts are passed through these lips for securing the frame in position on the mast and these guide lips also provide guiding means for the frame when the same is moved vertically on the mast from one position to another. The frame is provided with a pair of extended ears 18 at its top and bottom to which is hinged the receiving hopper frame 19, which frame comprises a vertical member 20 provided with a pair of ears 21 overlapping the ears 18 and having openings coinciding with the openings in said ears for the accommodation of the hinge rod 22. A horizontal hopper supporting arm 23 extends from this vertical member 20 and is secured at its free end to the hopper 5 and a pair of diagonally extending arms 24 extend from the top and bottom of the vertical member 20 and are secured to the bottom of the hopper 5 whereby the hopper is hinged supported by its frame from the head frame. During the normal operation of the apparatus, however, the hopper remains in a fixed position and in order to maintain the hopper in its proper relation with respect to the dumping position of the bucket a brace 25 extends from one arm 16 of the head frame to the top arm 23 of the swinging frame to hold the swinging frame against movement. The hopper 5, due to the fact that the swinging frame extends diagonally along one side of the mast, is supported at the front face, in an offset position, of the mast, and is provided with a hopper bottom 26 delivering into the trans-

195
110

versely extending chute 6, which chute at its delivery end is supported at the pivotal center of the hinged hopper frame and at its receiving end extends beneath the hopper 5. bottom 26 of the hopper 5.

The bucket 4 is of the hopper bottom type and is provided at its delivery mouth with a hinged gate 27 normally urged in a closed position by a suitable spring 28 operating 10 against a stop 29 on the bucket and against a stop 30 on a rod 31 connected at 32 with one of the side members of the gate 27. The delivery mouth of the bucket co-operates with a bridge chute 33 hinged at 34 to the 15 hopper 5 and normally maintained in non-bridging position, it being thrown into bridging position as the bucket rises by a roller 35 operating on a cam member 36, in a manner described in my co-pending application Serial No. 12,356, filed May 15, 1925.

I claim as my invention:

1. In an apparatus for handling building material the combination with a mast, of a bucket vertically movable on one face of said 25 mast, a head frame mounted on the opposite face of said mast, a delivery chute supported from said head frame and a chute hopper supported from said head frame in a plane beyond the plane of the bucket face of the mast 30 and delivering into said delivery chute.

2. In an apparatus for handling building material the combination with a mast, of a bucket vertically movable on one face thereof, a head frame mounted on the opposite 35 face of said mast, delivery chute supported from said head frame, an arm supported from said head frame and extending transversely of the mast, and a chute hopper supported from the opposite end of said arm and delivering 40 into said delivery chute.

3. In an apparatus for handling building material the combination with a mast, of a bucket vertically movable on one face thereof, a head frame mounted on the opposite 45 face of said mast, a delivery chute supported from said head frame, an arm hingedly sup-

ported on said frame at one end and having its opposite end extending to the bucket face of said mast and a chute hopper supported from the free end of said arm and delivering 50 to said delivery chute.

4. In an apparatus for handling building material the combination with a mast, of a bucket vertically movable on one face of said mast and having a delivery mouth opening 55 toward the side of said mast, a head frame mounted on the opposite face of said mast, a delivery chute supported from said head frame and a chute hopper supported from said head frame and at one side of said mast 60 and in a position to receive the contents of said bucket through said discharge opening and deliver said contents to said delivery chute.

5. In an apparatus for handling building 65 material the combination with a mast, of a bucket vertically movable on one face of said mast, a head frame adjustably mounted on the opposite face of said mast, a delivery chute supported from said frame, an arm 70 hingedly supported on said frame at one end and having its opposite end extending to the bucket face of said mast and a chute hopper supported from the free end of said arm and delivering to said delivery chute.

6. In an apparatus for handling building material the combination with a mast, of a bucket vertically movable on one face thereof, a head frame adjustably mounted on the opposite face of said mast, a delivery chute 80 supported from said head frame, an arm hingedly supported on said frame at one end and having its opposite end extending to the bucket face of said mast, a chute hopper supported from the free end of said arm and a 85 chute extending from said chute hopper to the delivery chute.

In witness whereof, I, CARL G. SCHMID, have hereunto set my hand at Indianapolis, Indiana, November, A. D. one thousand nine 90 hundred and twenty-five.

CARL G. SCHMID.
